(57) **CLAIM**

(21) Appl. No.: **29/265,385**

The ornamental design for a device for sizing a human female breast, as shown and described.

(22) Filed: **Aug. 30, 2006**

DESCRIPTION

(51) **LOC (8) Cl. 10-04**

FIG. 1 is a perspective view of a device for sizing a human female breast showing our new design;

(52) **U.S. Cl. D10/64**

FIG. 2 is a top plan view thereof;

(58) **Field of Classification Search D10/64;**

FIG. 3 is a right side elevational view thereof; and,

33/511-512

FIG. 4 is a bottom plan view thereof.

See application file for complete search history.

The design is symmetrical such that a left side elevational view is mirror image of a right side elevational view.

(56) **References Cited**

The broken line showings are included for the purpose of illustrating non-claimed subject matter and forms no part of the claimed design.
